UNITED STATES PATENT OFFICE.

JULIUS ADLER, OF JERSEY CITY, NEW JERSEY, ASSIGNOR OF ONE-HALF TO
ALICE LENDRY, OF NEW YORK, N. Y.

DESIGN FOR A CAPE.

SPECIFICATION forming part of Design No. 23,094, dated March 6, 1894.

Application filed December 23, 1893. Serial No. 494,603. Term of patent 3½ years.

To all whom it may concern:

Be it known that I, JULIUS ADLER, a citizen of the United States, residing at Jersey City, in the county of Hudson and State of New Jersey, have invented and produced a new and original Design for Capes, of which the following is a specification.

Reference is to be had to the accompanying drawings, forming a part of this specification, in which similar letters of reference indicate corresponding parts in all the figures.

Figure 1 is a perspective view of a cape showing my design. Fig. 2 is an enlarged exterior side elevation of part of the cape; and Fig. 3 is an enlarged inner side elevation of the cape.

The leading feature of my design consists in a plait-like configuration of the body A of

the cape and of a similar plait-like configuration of the collar B, and the plait-like configurations of the body A and collar B being united by zigzag lines D and E arranged opposite each other on the outside and inside, respectively, of the cape. A minor feature consists in the band-like figure C which runs parallel with the zigzag line D on the outside of the body A of the cape and the collar B disposed outwardly from its base at the zigzag lines D, E.

I claim—

The design for a cape as herein shown and described.

JULIUS ADLER.
